UNITED STATES PATENT OFFICE.

JOHN D. SHIPMAN, OF SAN ANGELO, TEXAS, ASSIGNEE, BY MESNE ASSIGNMENTS, TO
EMMA SHIPMAN, OF SAN ANGELO, TEXAS.

WINDOW-SASH LATCH.

Application filed November 5, 1925. Serial No. 66,997.

My invention relates to latches of the character shown and described in Letters Patent No. 1,114,391, issued to me October 20, 1914. In that invention the swinging latch member must be moved and held away from the rack in order to raise the window sash, otherwise it catches on the rack, as it was intended to do, and prevents the sash from being moved.

5 In the present invention, I have provided a construction and arrangement by means of which I have eliminated the cord or cable for moving the gravity latch and have provided a form of rack with cam portions 10 which move the swinging latch outwardly as the sash is moved, but with holding portions above the cam portions for receiving the latch member as the sash moves in the opposite direction and holds it in that position. I have also provided in connection therewith means for catching said latch member to prevent the sash from being raised from a predetermined position without moving the latch element from the rack.

15 20 25 In order to explain my improvements, I have illustrated the same on the accompanying sheet of drawings, in which,—

Figure 1 is a fragmentary view of a window sash and frame, showing my invention applied thereto;

Figure 2 is a similar view showing a slightly modified form of rack or frame member;

Figure 3 is a detail, showing a short locking piece for use in connection with a rack of the character shown in Fig. 1;

Figure 4 is a similar view of a slightly different form of locking piece; and

Figure 5 is a perspective view of the 40 gravity latch to be mounted on a sash.

Referring to the drawings, 1, designates a window frame, and 2, a window sash moving therein. Mounted on the sash is a swinging or gravity latch which includes a base plate, 3, with a strap, 4, and a pivoted latch member, 5, said latch member having the hook portion, 5^a, and the finger, 5^b. It will be noted that the lower end of said latch member is heavier and that said latch will swing by gravity to extend the hook portion, 5^a, forwardly, or toward the window frame, as it swings around its pivot 6.

Mounted along the inner edge of the window frame, 1, is a rack, 7, made of channel iron, with struck in cam elements,

8, attached at their upper ends and forming an opening, as 9, below each of said cam elements or portions, 8. At the lower end of said member, 7, are two holes, as 10, 10, without the cam elements, and into these 60 holes the hook portion of said latch can swing and thus lock the sash against movement upwardly, or downwardly, without first manually swinging the latch member outwardly. This is intended to make it 65 possible to raise the sash a little and hold it there until the latch is manually moved.

In Fig. 2, I have shown a modified form of rack, made of solid material, with the cam portions, 11, and the shoulders, 12, the 70 cam portions operating to automatically swing the latch back as the sash is raised, and if the sash is allowed to move downwardly, the latch catches on the shoulder, 12, for supporting the sash in the desired 75 position. The lower end of this rack is provided with two downwardly facing hooks, as 13, 13, to catch the latch and prevent the sash from being raised without first moving the latch away from it. The 80 hook portion 5^a, of said latch will catch on the hook 13, or it will rest on top of one of said hooks, 13, if it is desired to support the sash raised a short distance from its lowermost position.

Instead of having the racks, 7, and 11, provided, respectively, with the holes, 10, 10, or the downwardly facing hooks, 13, 13, short pieces of rack can be used. In Fig. 3 is shown a short piece of channel iron, 14, 90 with two holes, as 15, 15, therein. In Fig. 4 is shown a short piece, 16, with two downwardly facing hooks, 17, 17, formed thereon. These can be used at the base of the window frame to hold the window sash from being 95 raised further after it has been raised a short distance and the hook portion 5^a has entered one of the holes, or catches on one of the hooks, 17, 17.

When it is desired to raise the window 100 higher, it is only necessary to hold the swinging latch member out until its hook portion 5^a passes the holes, 10, 10, or the hooks, 13, 13, as the case may be and as the sash is raised, the cam portions, 8, 8, or 11, 11, as the case may be automatically swing said latch member outwardly until it passes the openings, 9, or the shoulder, 12, whereupon, if the sash is let move down again, 105 said latch catches either in the hole, 9, or 110

on the shoulder, 12, depending on which form of rack is used. In one case the lower edge of the hole, 9, holds the latch, and the sash, and in the other case the shoulder 12, 5 holds them. As the window sash is raised further, it is not necessary to have a cord or to hold the latch out, for the cam portions prevent it from catching and the sash can be pushed up without the necessity of touching the latch at all.

What I claim and desire to secure Letters Patent for is:—

In combination with a window frame and sash sliding therein, a base plate mounted 15 on the side of the sash adjacent the window frame, a strap secured at its opposite ends to the top and bottom of said base plate with its middle portion spaced from said base plate, said strap being narrower than 20 said base plate, a latch member pivotally connected at its upper end between said strap and said base plate and swinging in the space therebetween, said latch having a

portion projecting over the base plate not covered by said strap and having an outwardly projecting finger member for manually moving said latch, the opposite edge of said latch having an upwardly projecting hook portion normally swinging toward said window frame, and a rack made of channel 25 iron with struckin portions attached at their upper ends and bent inwardly to form cam portions to move said hook portion away from the frame as said sash moves upwardly and prevent it from catching, some of said struckin portions being omitted and holes being formed in the outer face of said channel iron, whereby said hook portion will catch by its lower side or by its upper side 30 and prevent said window from moving up or down, as the case may be, substantially as shown and described.

Signed at Los Angeles, Los Angeles County, California, this 27th day of October, 1925.

JOHN D. SHIPMAN.
